UNITED STATES PATENT OFFICE.

JOSEPH BARNEY HENDRIX, OF WALSENBURG, COLORADO, ASSIGNOR OF ONE-HALF TO
ROBERT F. LAMONS, OF WALSENBURG, COLORADO.

RADIATOR.

Application filed September 21, 1923. Serial No. 664,083.

My invention relates to certain new and useful improvements in radiators such as are especially adapted for use with internal combustion engines in automobiles and the like; 5 it particularly has for its object to provide a radiator of such construction that it will be proof against leakage due to freezing and of such construction that it may be quickly and easily repaired if and when necessary. 10 Another object of the invention is to provide a means to prevent the radiator blowing up by an over-amount of steam pressure generated within the same should the overflow or vent pipe for any reason become 15 clogged.

Again it is an object of the invention to provide a radiator whose tubes can be standarized and made of tubing sections of long lengths from which the desired length 20 piece can be cut to fit any water radiator which may be in need of repair, by simply selecting from a few stock tubes a tube of proper width and thickness.

In its general nature the invention comprising a radiator of the usual form consisting of top and bottom water tanks united by water tubes spaced apart for the passage of air, the top and bottom water tanks, however, being provided with wide openings 25 opposing one another and surrounded by short flanges to which the water tube sections may be soldered; each water tube section is of approximately rectangular cross section and so formed as to be laterally expandable in the event the water within the 30 radiator freezes. The water tube sections are spaced apart by corrugated fins held non-rigidly in place and adapted to give when the water tube expands so as to permit 35 the expansion of the water tubes due to freezing of the water, the fins being of sufficient resiliency to assume their original form when the expanding tubes contract again on thawing out of the ice.

40 The radiator also includes a neck which communicates with the water tank through a perforated partition or strainer whereby solid matter which would tend to clog the radiator is prevented from entering the water tanks and tubes, and the neck is also provided with a cap in which is provided a vent valve to relieve steam pressure.

In its more subordinate nature the inven-

tion furthermore resides in those novel features of construction, combination and arrangement of parts, all of which will be first fully described, then be specifically pointed out in the appended claim, reference being had to the accompanying drawings, in which

60 Figure 1 is a perspective view of a radiator embodying my invention.

Figure 2 is a rear elevation of the same.

Figure 3 is a horizontal section of the 65 radiator.

Figure 4 is a perspective view of one of the water tubes.

Figure 5 is a perspective view of one of the fins.

Figures 6, 7, 8 and 9 are respectively diagrammatic horizontal sections of modified forms of the radiator embodying my invention.

In the drawings, in which like numerals of reference indicate like parts in all the figures, it will be seen the radiator is composed of the usual top water tank 10 and bottom water tank 7 united together by the vertical water tubes which constitute one of the essential features of my invention. The water tanks have opposing openings surrounded by short flanges 8 and 12 to which the flanges 5 of the water tubes are soldered. The flanges of the water tubes are made of sufficient width so that when the tubes are 80 all soldered in place the opposing openings of the top and bottom tanks will be closed by the flanges of the tubes which thereby 85 form a covering for such openings.

Each tube comprises a front wall 1, a back 90 wall 2 and side walls 3, the metal of the side walls being folded inwardly, as at 4, to form vertical water passages in each water tube and to allow the water tubes to expand when the water freezes. Each tube also includes 95 the end flanges 5.

In building up my invention or in making repairs the flanges 5 are soldered together and to the top and bottom water tanks by solder as at 6, using an ordinary fork solder 100 iron.

9 designates the cold water outlet to the bottom tank 7 and 22 designates the hot water inlet to the top water tank 10. 11 is the neck of the tank 10 through which water is 105 introduced into the radiator, the same pass-

ing through the perforated bottom 13 of the neck 11.

The vent pipe 14 also passes through the bottom of the neck (top of the top tank 10) 5 and passes down to the bottom of the radiator as in the usual practice.

The neck 11 is provided with the usual cap 23 in which, in my present invention, there is provided a back check valve 15 which, 10 while allowing air to enter, will open against pressure from within the radiator to blow off steam accumulations and prevent the radiator expanding in the event the vent pipe becomes clogged for any reason.

15 16 designates the fins which are placed between adjacent water tubes. These fins are preferably of the conventional type having air holes and deflectors 17 to break up the air currents and deflect the air against 20 all exposed surfaces of the water tubes for cooling purposes. These fins are not soldered in place as is the usual radiator practice, but are of a length less than the full height of the tube and are held in place only by 25 retaining flanges. They are of sufficient yieldability or resiliency so that when the tubes expand on the water freezing the fins will be compressed accordingly without exerting undue resistance to the expansion of 30 the tubes and after the tubes re-assume their initial position on thawing, the fins will likewise assume their normal positions.

In order to hold the fins in place against 35 edgewise or front and back movement, the back of the radiator may be provided with straps 18 that are soldered to the radiator tubes and the front of the radiator may be provided with a wide mesh screen 19 which likewise may be soldered at intervals to the 40 tubes or which may be held in place by the usual radiator shell covering not shown (this is a covering usually placed over the radiator to give finish to the appearance of the same).

20 15 20 are corner braces for the overhang of the top water tank, the corner braces being soldered to the side plates 24 that connect the top and bottom water tanks together, the side plates 24 having ears 25 soldered to the top tank and side brackets 21 have portions 26 and 27 projecting under and soldered to the bottom tank. 21 designates the 50 side brackets which are secured to the plate 24 by bars 24^a and by which the radiator is mounted on the chassis frame of the automobile.

It is to be noted that the back straps 18 include cross members which are soldered to the flanges of the side plates 24 and serve to brace the radiator against lateral distortion.

In the practical use of my invention if a 10 radiator tube becomes damaged it is only necessary to remove the screen 19 and apply a hot fork soldering iron to the flanges 5 after first removing the fins 16 at each side

of the tube. This will melt the solder of the particular tube that is damaged and permit it to be withdrawn edgewise through the front of the radiator. The operator then selects his stock tube of proper cross sectional shape and size, cuts off a length of the required amount with his tin snips and bends down a pair of flanges 5, after which the new tube section thus obtained is inserted in place of the old one and soldered by the use 70 of a fork soldering iron as before, after which the fins 16 are replaced as is also the screen 19 and the radiator will be ready for use.

As shown in Figures 6 to 9 inclusive the 80 invention may be applied to different types of radiators than the one shown in Figures 4 and 5. The staggered tubes form abutments for one edge of the fins while the screen and cross braces form the respective abutments 85 for the other edges of the fins to hold the same in place as will be clear by reference to Figures 6 to 9 inclusive.

From the foregoing description, taken in connection with the accompanying drawings, 90 it is thought the construction, operation and advantages of my invention will be clear.

Attention is however called to the fact that with my construction of radiator the water flow is straight from the top reservoir 95 down to the bottom reservoir, thus the passages of the tubes, being of relatively wide form, offer little or no chance for clogging in the event that sediment gets into the tank; the provision of the apertures 13 in the top 100 of the top water tank, i. e. in the bottom of the neck, acts as a strainer, however, prevent sediment entering the radiator when filling the same and in that way reduces the liability of clogging due to the sediment.

It will also be noted that the fins are punched in such way that the air passing through between the tubes is caught and deflected against the sides of the tubes thus increasing the cooling qualities of the radiator. The fins also serve as springs between the water tubes so that if the water freezes and pushes out against the fins they will be pushed back when the ice in the tubes thaws out again.

114 What I claim is:

In a radiator, a top and a bottom tank having opposing portions each provided with an opening, the opening in one being opposite the opening in the other, a series of flat water tubes of substantially rectangular cross section having flanges at each end, those at one end of a tube adapted to lie in contact with those of the same end, of adjacent tubes and constitutes closures for said openings and spacers for said tubes, means for effecting a water seal and acting as a holding instrumentality between the adjacent flanges of said tubes and the tank whose opening is closed thereby, said tubes adapted 120 125 130

to bellie outward when water within them freezes, fin plates located between the tubes, said fin plates being corrugated and of an over-all length slightly less than the distance between the top and bottom flanges of the tubes, and means restraining said fin plates against front and back displacement,

said fin plates when said restraining means is removed being themselves bodily slideable through the front of the radiator for removal or replacement without disturbing the tubes, substantially as specified. 10

JOSEPH BARNEY HENDRIX.
